UNITED STATES PATENT OFFICE.

JAMES S. FORD, OF IRVING COLLEGE, TENNESSEE.

WINDOW, PICTURE, OR OTHER FRAME.

SPECIFICATION forming part of Letters Patent No. 369,512, dated September 6, 1887.

Application filed May 4, 1887. Serial No. 237,113. (No model.)

To all whom it may concern:

Be it known that I, JAMES S. FORD, a citizen of the United States, residing at Irving College, in the county of Warren and State of 5 Tennessee, have invented a new and useful Improvement in Window, Picture, or other Frames, of which the following is a specification.

My invention relates to improvements in 10 window, picture, or other frames; and it consists in a certain novel construction and arrangement of parts for service, fully set forth hereinafter and claimed.

The object of the invention is to provide 15 means whereby the glass may be secured in place in the said frames without the use of points, putty, or tacks; and it consists in grooving the inner edges of the sash rails and stiles and constructing one of the said rails so as to 20 be removable, to enable the same to be taken out.

My invention consists, further, in certain details of construction, hereinafter more fully described, and illustrated in the accompanying 25 drawings, in which—

Figure 1 is a perspective view of a sash embodying my improvements. Fig. 2 is a vertical section on the line xx of Fig. 1. Fig. 3 is a similar view on the line yy of Fig. 1. Fig. 30 4 is a front elevation on a smaller scale showing the top rail removed. Fig. 5 is a detail view of the horizontal stile.

Referring to the drawings by letter, A designates the frame of the sash, comprising the 35 bottom rail, B, the side rails, C C, and the removable top or meetings rail, D, all of which rails are grooved on the inner edges to receive the glass.

E designates the vertical, and F the horizontal, stiles or strips for the glass, grooved on 40 both sides, the said horizontal strips being removable, as shown in Fig. 4. The said edges of the rails or strips are beveled or beaded, as seen at $c e$, to give a finish to the appearance 45 of the sash, and the ends of the horizontal strips are grooved or recessed to fit the said beveled or beaded edges and slide thereon. The upper ends of the strips E are extended to 50 form tenons e , and the top rail, D, is correspondingly mortised to receive the said tenons.

To put the glass in place remove the top

rail and the horizontal strips and slide the lower sheets of glass down in the grooves, replace the strips F, insert the upper sheets of glass, and replace the top rail in position.

If the meeting-rail of the lower sash is removable, there is no necessity for any fastening thereto, as the tenons will hold it in place; but in cases where it is needed I provide either the straps or plates G, secured across 60 the joint between the side and top rail, or the hook and stud H, in the same position, both of which are shown in their operative positions in the drawings, Fig. 1. Other means of securing may be used in this connection, and I do not limit myself to those named.

It will be seen from the foregoing that a broken pane of glass may be replaced in a very short space of time by a mere novice, and when in place will be as secure as if secured 70 by the ordinary points and putty. Further, by the means herein described a sash is made similar on both sides, and consequently reversible, this being an advantage from the fact that the side of a sash which is exposed to the 75 weather is more liable to decay than the other, and therefore if the sash is reversed it will obviously outlast two which cannot be reversed.

It will be seen that if the sash is provided 80 with only one or two panes the same manner of securing them in place may be employed as herein described, and there is much less liability of breaking the said pane in putting it in place in the said manner than there is 85 when they are fastened with putty. This means of securing glass may be applied to mirrors, pictures, &c., and will be found very effective and a great saving of time.

I am aware that heretofore sashes have been 90 constructed with a removable rail, and that there have been grooves formed in the inner edges of the rails to receive the glass, and I therefore do not claim this, broadly; but I am not aware that the peculiar construction herein 95 described has been heretofore employed, having special reference to the movable horizontal strips, having the recessed ends to slide on the beaded edges of the vertical rails and stiles, the vertical stiles provided with tenons to 100 enter mortises in the movable rail and hold it thus without additional securing, and the

special means of securement of the said movable rail when the circumstances demand the same.

Having now described my invention, I 5 claim—

1. A sash having the grooves in the inner edges of the rails thereof, the vertical strips or stiles having the tenons on the ends, the removable sliding strips, and the removable rail D, provided with mortises to receive the said tenons, substantially as and for the purpose set forth.

2. A sash having the rails and the inner strips thereof beaded or beveled on the inner

edges, the horizontal strips having the grooved 15 or recessed ends to slide on the said beaded edges, the removable rail D, and devices, substantially as described, for securing said removable rail in place, substantially as and for the purpose hereinbefore set forth.

20

In testimony that I claim the foregoing as my own I have hereto affixed my signature in presence of two witnesses.

JAMES S. FORD.
